(57) **CLAIM**

The ornamental design for a supple impact simulated trash can assembly, as shown and described.

DESCRIPTION

FIG. 1 is a perspective view of a supple impact simulated trash can assembly in accordance with the present invention.

FIG. 2 is a front view thereof.

FIG. 3 is a rear view thereof.

FIG. 4 is a left end view thereof.

FIG. 5 is a right end view thereof.

FIG. 6 is a top view thereof.

FIG. 7 is a bottom view thereof.

FIG. 8 is a perspective view showing a lid of the supple impact simulated trash can assembly in accordance with the present invention.

FIG. 9 is a front view thereof.

FIG. 10 is a rear view thereof.

FIG. 11 is a left end view thereof.

FIG. 12 is a right end view thereof.

FIG. 13 is a top view thereof.

FIG. 14 is a bottom view thereof.

FIG. 15 is a perspective view showing a trash can of the supple impact simulated trash can assembly in accordance with the present invention.

FIG. 16 is a front view thereof.

FIG. 17 is a rear view thereof.

FIG. 18 is a left end view thereof.

FIG. 19 is a right end view thereof.

FIG. 20 is a top view thereof; and,

FIG. 21 is a bottom view thereof.

The lid and the trashcan are shown separated in FIGS. 8 through 15 and 16 through 21 respectively for convenience of illustration.

The inflating valves shown in broken lines in some of the figures are to show environment and are not part of the claimed design.
